BOOKMARK

Leon Kardorff, New York, N. Y.

Application August 8, 1941, Serial No. 406,065

5 Claims. (Cl. 116—119)

My invention relates to bookmakers.

One of the objects of my invention is to provide a bookmarker in which the marker element is transparent so that there will be no difficulty in reading the printed page under the marker element. Further, the marker element is so shaped that upon turning a page the travel of the page on the sloping engaging edge of the marker will cause the marker to be raised to permit the passage of the page and thereafter fall in place again, marking the new page.

In markers which accomplish the above indicated purposes, simplicity of manufacture and assembly are desirable features, since the markers are made in large quantities. By making the marker element itself of flexible resilient material and providing the cutaway portion, the marker and slot through which the support passes can be deformed so as to permit the insertion of the head of the support for the marker. Upon release of the marker element, it will, because of its resilient nature, spring back into operative position. A further form of device is one in which the support carrying the head is provided with a cutaway portion, the support being also made of flexible resilient material which will permit the deformation of the support so that the head may be inserted through the slot in the marker element.

In the drawing:

Fig. 1 is a perspective view of my complete bookmarker construction.

Fig. 2 is a view in side elevation of the bookmarker showing it in place in the book, the raised position of the marker element being indicated in dotted lines.

Fig. 3 is a perspective view of a book with the marker in place and a page of the book in the process of being turned.

Fig. 4 is a perspective view of a book with the marker in place after the page has been turned.

Fig. 5 is a perspective view of a modified form of my marker in which the support is provided with a cutaway portion permitting its deformation during assembly.

Referring to the drawing, Figs. 1 to 4, I have shown a bookmarker which is adapted to be made of flexible resilient material, preferably transparent, such as some of the transparent flexible resilient resins which are designated under the general term "plastics." I have shown an integral body support and head in which the numeral 1 indicates a body which is adapted to fit in and lie between the pages of a book, as more clearly illustrated in Fig. 4 in which the

body 1 is shown in dotted lines lying between the pages of a book 2. The body 1 is provided with a cutaway portion 3 providing a tongue 4 which is adapted to fit over the page of a book so as to hold the body 1 securely in place. In using the marker, the body 1 is placed at a point sufficiently far ahead of the page being read to hold the body 1 securely in place, and the tongue 4 is slipped over a page or pages to securely hold the body 1 in position during use.

The body 1 is struck up at substantially right angles to form a support portion 5 having a cutaway portion 6 on either side thereof over which is adapted to slide a groove 7 formed in a marker 8 which is provided with sloping edges 9 and 10. The sloping edge 10 is adapted to contact the edge 11 of a page 12 which, when raised as indicated in Fig. 3, causes the marker element to rise and slide upward on the support 5.

The support 5 is provided with a head 13 sufficiently large to prevent the head 13 from sliding through the slot 7 formed in the marker 8. This permits the marker 8 to slide up and down on the reduced portion 6 of the support 5, but prevents the marker 8 from becoming disengaged from its sliding position on the support 5.

In assembly, the flexible, resilient, transparent marker 8 is deformed by pressure along the lines of a slot 14 having an enlarged end 15 formed in the marker. This slot 14 and enlarged end 15 lie adjacent and substantially at right angles to the slot 7. By deformation of the marker 8, the head 13 can be slipped through the slot 7, and the parts then spring back into the position shown in Fig. 1 by reason of the resilience of the parts. During the assembly, the support 5 can also be deformed if necessary to permit the slot 7 to be slipped over the head 13 of the support 5.

In another form of my device, the marker 8 may not necessarily be constructed with the slot 14 and its enlarged end 15 thereof. This is not prohibited. However, in order to assemble the parts, I provide the support 5 with a cut out portion 16 as illustrated in Fig. 5. By pressing together the two sides of the support 5, as indicated by dotted lines in Fig. 5, the slot 7 of the marker 8 may be slipped over the head 13 of the support 5. Then support 5 springs back into the position shown in solid lines in Fig. 5 and the device is completely assembled for use.

I desire that my invention be limited only by the scope of the appended claims and the showing of the prior art.

I claim:

1. A book marker for a book having pages, said

marker comprising a body portion adapted to be held between the pages of the book, a vertical support carried by the body, a cut away portion along each edge of the vertical support, a flexible resilient marker having a slot therein whereby the marker can slide in the cut away portions in the support, an elongated cut in the marker that communicates with and is at right angles to the slot so that in flexing a portion of the marker adjacent the elongated cut the marker can be positioned in the cut away portion of the support.

2. A book marker for a book having pages, said marker comprising a body portion adapted to be held between the pages of the book, a vertical support carried by the body, a cut away portion along each edge of the vertical support, a flexible resilient transparent slide marker having a slot therein whereby the marker can slide in the cut away portions in the support, an elongated cut in the marker that communicates with and is at right angles to the slot so that in flexing a portion of the marker adjacent the elongated cut the marker can be positioned in the cut away portion of the support.

3. A book marker for a book having pages, said marker comprising a body adapted to be held between the pages of the book, a flexible resilient vertical support carried by the body, a cut away portion along each edge of the vertical support, a slideable marker having a slot whereby the marker can slide in the cut away portions, and a cut in the vertical support whereby the vertical support can be deformed to permit the slot in the marker to be fitted in the cut away portions.

4. A book marker for a book having pages, said marker comprising a body adapted to be held between the pages of the book, a flexible resilient vertical support carried by the body, a cut away portion along each edge of the vertical support, a cut therein, a slideable marker having a slot whereby the marker can slide in the cut away portions, an elongated slit in the marker that communicates with and is at right angles to the slot, said cut and elongated slit permitting deformation of the vertical support and the marker whereby the slot in the marker can be disposed in the cut away portions.

5. A book marker for a book having pages, said marker comprising a body for insertion between pages of the book, a flexible resilient support element carried by one end of the body and extending perpendicularly to the plane of the body and the pages of the book, a slideable flexible marker element having a slot formed therein adjacent one end thereof said slot being of a length corresponding to the width of the support element and having said support element extending therethru, and a head on the free end of said support element of a width greater than the length of said slot to prevent undesired removal of the slideable marker element from said support element, at least one of said support and slideable marker elements having a slit portion to render that element having a slit portion deformable to provide for assembly and separation of said elements.
